UNITED STATES PATENT OFFICE

149,408

DESIGN FOR A BICYCLE

Royal J. Fuhs, Louisville, Ky.

Application May 17, 1946, Serial No. 129,813

Term of patent 14 years

(Cl. D90—8)

To all whom it may concern:

Be it known that I, Royal Joseph Fuhs, a citizen of the United States of America, residing at Louisville, county of Jefferson, State of Kentucky, have invented a new, original, and ornamental Design for a Bicycle, of which the following is a specification, reference being had to the accompanying drawing, forming a part thereof, wherein

The side of the bicycle not shown is similar to the side shown.

I claim:

The ornamental design for a bicycle, as shown and described.

ROYAL J. FUHS.
